UNITED STATES PATENT OFFICE.

JOHN PODMAJERSKY, OF CHICAGO, ILLINOIS.

DESIGN FOR A SIGNAL-LIGHT AUTOMOBILE FENDER.

Application filed October 24, 1923. Serial No. 7,577. Term of patent 14 years.

To all whom it may concern:

Be it known that I, JOHN PODMAJERSKY, a citizen of the Republic of Czechoslovakia, residing at 571 W. 18th Street, in the city of Chicago, county of Cook, and State of Illinois, have invented a new, original, and ornamental Design for a Signal-Light Automobile Fender, of which the following is a specification, reference being had to the accompanying drawing, forming part thereof.

Figure 1 is a side elevation of a signal light automobile fender embodying my new and ornamental design.

Figure 2 is a plan view thereof.

Figure 3 is an end view thereof.

I claim:

The ornamental design for a signal light automobile fender as shown.

JOHN PODMAJERSKY.
